METHOD AND APPARATUS FOR BODYING LIQUIDS

Robert A. Carleton, New Rochelle, N. Y., assignor
to National Electric Heating Co. Inc., New York,
N. Y., a corporation of New Jersey

Application October 23, 1929, Serial No. 401,941
Renewed February 7, 1935

14 Claims. (Cl. 37—12)

This invention relates to improvements in methods and apparatus for treating liquids, the physical or chemical properties of which are subject to a definite change when the liquid is subjected continuously to a substantially uniform, predetermined temperature for a predetermined period of time.

More particularly the invention relates to improvements in methods and apparatus for continuously bodying unsaturated oils of the ester type including linseed, and other organic oils, such as vegetable, animal, and marine, which are normally in a liquid state, or which may be rendered liquid by heat or other treatment. Such oils when properly polymerized may be used in the manufacture of paint, varnish, lithographic ink, linoleum, etc., and in some instances in the manufacture of lacquer, resin, and the like.

In usual methods of polymerization the oil is heated in portable kettles of from one hundred to two hundred gallons capacity mounted upon trucks by which the kettles are wheeled over fixed fires of coke, gas, or oil, where the liquid is heated to the desired polymerizing temperature which ordinarily ranges from four hundred fifty to six hundred twenty-five degrees Fahrenheit depending upon the kind of type of oil, and the degree of body required for the purpose to which it is to be applied.

The oil after being heated to the polymerizing temperature is maintained at such temperature for a period varying from one hour to ten hours, or longer, for the required polymerizing or bodying of the oil to take place.

When coke or other fires for heating are employed the usual means for controlling the oil temperature is by withdrawing the kettle from the fire should the temperature become too great and replacing it over the fire when it is desired to increase the temperature. During this operation the oil must be agitated or stirred to prevent the burning of the layer of oil which is in contact with the kettle bottom at which point the temperature is from one hundred to three hundred degrees greater than that of the body of oil in the kettle.

Furthermore, the circulation which takes place by convection or is caused by the stirring is not sufficiently complete to bring all of the globules of oil in contact with the heating surface and consequently uniform polymerizing of the oil is seldom, if ever, attained.

The high temperature to which the oil is subjected in such open kettles has several injurious effects upon the oil which includes cracking or

decomposition of the oil, forming carbon which causes a darkening or discoloration of the oil, generation of certain acids and other compounds which have an injurious effect upon the final product with which the oil is to be combined and loss of a considerable amount of oil by volatilization.

Where the oil is thus treated in open kettles there is great danger of the oil becoming ignited from the fumes, or from spilled material, which comes in direct contact with the fire.

The principal object of the invention is to provide a novel process and apparatus for quickly heating a flowing stream of oil, of the character specified, to a predetermined temperature and maintaining the flowing liquid at said temperature a predetermined period of time.

A further object of the invention is to provide a method and apparatus by means of which substantially all the particles of the liquid will be uniformly subjected to the same predetermined temperature.

Another object of the invention is to provide a method and apparatus for treating liquids in which injurious effects of heat upon the liquids, such as those above mentioned, will be wholly or substantially avoided.

More specifically the invention comprises a method for bodying oils of the character specified which consists in confining a flowing stream of oil from contact with the air, heating the flowing liquid rapidly to a desired polymerizing temperature, maintaining the liquid at substantially said temperature until the desired degree of polymerization is effected, and then preferably quickly cooling the liquid to arrest polymerization.

The present method consists further in rapidly heating a flowing stream of the liquid of small cross sectional area to the desired polymerizing temperature, then retarding the flow of said liquid by increasing the cross sectional area of the stream, subjecting the larger stream to the same polymerizing temperature for a predetermined length of time sufficient to cause the desired polymerization to take place, and then quickly cooling the liquid.

The method further consists in correlating to the polymerizing temperature the period of time during which the liquid is subjected to said polymerizing temperature to produce the desired polymerization.

The method of polymerizing linseed oil, and other unsaturated oils of the ester type, as above described, comprises quickly heating a flowing

stream of the oil of cross sectional area to the necessary polymerizing temperature within a short period of time which may be varied from a few seconds to approximately a minute according to the character of the oil being treated, thereupon increasing the cross sectional area of the flowing stream of liquid so that its rate of flow is retarded, maintaining the enlarged flowing stream at approximately the polymerizing temperature aforesaid while confined from contact with the air at approximately atmospheric pressure for a sufficient period of time to permit the desired degree of polymerization, and then arresting polymerization by quickly cooling the oil. The polymerization of linseed oil is usually effected by maintaining the oil at a temperature approximating 650-degrees for a period varying from a few seconds to several minutes according to the character of the oil, but it is found that in the treatment of linseed oil the use of higher temperatures, for example, from 650 to 775 degrees has a marked effect on the time required to produce a desired viscosity and also upon the gloss and hardness of the film of the product. In the treatment of other unsaturated oils of the ester type the polymerizing temperature and the period required for polymerization is, of course, varied in accordance with the characteristics of the particular oil employed.

It is found that in the treatment of certain unsaturated oils of the ester type it is necessary to heat the oils quickly as the polymerization or bodying of the oil is critical and takes place very rapidly, and if maintained at the polymerizing temperature for too long a time the oil will set into a solid mass comparable with sponge rubber. However, if such oils are carried quickly through the polymerizing zone the reaction slows down and can be controlled at higher temperatures more easily, thus making it possible to process such oils under conditions of greater control, and that at these higher temperatures sufficient time is available to enable the properly polymerized oil to be quickly cooled so that it will retain permanently the desired structure.

The method further contemplates effecting a heat exchange between the discharging polymerized or bodied oil and the fresh oil supplied to maintain the continuously flowing stream, thereby economizing the amount of heat required to effect such polymerization.

An apparatus for performing the method forming the subject matter of this invention is illustrated in the accompanying drawings, in which,

Fig. 1 is a diagrammatic view of the apparatus;

Fig. 2 is a plan view of the same, the cover of the casing enclosing the effective portion of the apparatus being omitted;

Fig. 3 is a vertical longitudinal sectional view of the apparatus broken away centrally because of the limitation of the sheet of drawings;

Fig. 4 is a transverse vertical section on line 4—4 Fig. 3, viewed from the right toward the left;

Fig. 5 comprises a vertical longitudinal sectional view of the electric heating mechanism for raising the liquid to polymerizing temperature, and a preferred means for supplying a polyphase electric current to said heating means, together with automatic means for controlling the current supplied to the heating means; and,

Fig. 6 is a transverse vertical sectional view of the electric heating mechanism illustrated in Fig. 5.

The apparatus will be described as used in poly-

merizing linseed oil, but is adapted for treatment of other liquids in a similar manner.

The apparatus illustrated diagrammatically in Fig. 1 comprises a casing 1, preferably of rectangular form, having at one end a compartment 2 in which a preferably electric heater 3 is enclosed adapted to heat a flowing current of liquid of small cross sectional area to the desired polymerizing temperature during a period of twenty to fifty seconds within which no cracking or decomposition of the oil will take place because of the shortness of the time. The stream of liquid flowing from the heater 3 is discharged into the lower end of the compartment 2 which forms the first compartment or section of a reactor through which the liquid is directed in a channel or channels 4 of very much greater cross sectional area, thereby retarding the rate of flow of the liquid.

The term "reactor" is used herein to define a container such as a conduit, chamber, or receptacle, which receives the heated liquid, and in which it is retained while polymerization, or some other desired physical or chemical change requiring a definite period of time takes place.

The liquid while flowing through the reactor 25 desirably is subjected to a slight vacuum and is maintained at substantially the polymerizing temperature preferably by electric heating means and the period of time required for the flow through the reactor or a portion thereof is so 30 correlated to the polymerizing temperature as to complete the desired polymerization of the oil during the flow therethrough. The reactor is so constructed that the period of time required for the liquid to flow through it, or a predetermined portion of it, at the time during which the oil is maintained at the desired polymerizing temperature, may be varied from a short time to several hours in accordance with the characteristics of the particular oil being treated. Where 35 high temperatures are employed considerable heat is generated by the polymerizing reaction which tends to increase the temperature of the oil and the reactor is provided with suitable heat-exchanging means for maintaining the oil during 40 the polymerization stage constantly at substantially the desired polymerizing temperature.

The reactor is provided with a final compartment 5 which serves as a cooling chamber to reduce the temperature of the liquid quickly and 50 arrest polymerization. The polymerized or bodied liquid discharged from the reactor passes through a suitable pipe 6 to storage tanks 7.

The fresh oil preferably is drawn from one or 55 more supply tanks 8 by a pump 9 and forced at a constant rate through a pipe 10 which extends into the final or cooling compartment 5 and is provided therein with a sinuous section 11 to provide a large heat-exchanging surface in contact with the liquid flowing from the reactor. A 60 pipe 12, extending from the lower end of the sinuous section 11, communicates with the inlet end of the conduit of the heater.

The heater is so constructed as to raise the 65 temperature of the liquid quickly to the predetermined polymerizing temperature. The reactor is provided with suitable, preferably electric heating, means to maintain the flowing stream of oil therethrough at substantially the constant polymerizing temperature during its entire passage 70 therethrough.

The final outlet passage from the reactor is so constructed that the highly heated oil will flow in contact with the surfaces of the pipe containing the fresh oil supplied to the heating conduit and 75

by heat exchange will not only reduce the temperature of the heated oil sufficiently to arrest polymerization, but will also preheat the oil or liquid which is supplied to the heating conduit.

5 The apparatus thus generally described is suitable for performing the method of quickly heating a flowing stream of oil or other liquid, maintaining the same at a predetermined polymerizing temperature for such predetermined period of 10 time as is required to effect the desired polymerization of the oil, then quickly cooling the oil to arrest polymerization and finally delivering the bodied oil to suitable containers.

15 Various details of construction of the apparatus including mechanism for automatically regulating the supply of the electric heating current and interruption of the heating current upon cessation of flow of the liquid will be hereinafter more fully described.

20 While any suitable means may be employed for quickly heating the liquid to the desired polymerizing temperature, preferably electric heating means are employed which will heat the liquid uniformly and quickly throughout during its passage through a conduit of small cross sectional area, the heating means being so constructed that carbonization or other injurious effects to the oil will be avoided.

25 A preferred form of heating apparatus is illustrated in Figs. 5 and 6 in which the heater 3 is illustrated as comprising a casing, which as shown is of rectangular form but which, of course, may be made of circular form, having a front wall 13 and a rear wall 14 narrowly spaced therefrom with 30 suitable side walls 15 and 16 and end walls 17 and 18. The inlet 12 for the liquid extends through the upper end wall of the casing and an outlet 19, which is located centrally of the casing and at a considerable distance from the bottom 35 thereof, serves to discharge the heated liquid through a delivery conduit 20 into the initial chamber of the reactor casing 1. Electric heating units are arranged in this casing in such a manner 40 as to provide a conduit or conduits through which the liquid will circulate in contact with the heating units in a sinuous or preferably spiral direction.

45 In the construction shown in Fig. 5 suitable heating units are provided for a three-phase electric heating current and comprises parallel ribbons 21, 22 and 23, of material of high electrical resistance such as Monel metal, one of the many chrome steel alloys, or other material having also suitable resistance to corrosion by the liquid being 50 treated. The edges of these ribbons of high resistance material desirably are set into or otherwise secured to the inner faces of the side walls 13 and 14 which are formed of, or lined with, suitable insulating material, such as porcelain, "Pyrex", bakelite, etc., in such a manner as to provide conduits for the material which extend in parallelism to the sides of the edges of the receptacle and concentrically toward the center thereof, all of said conduits finally communicating 55 with the central passage 24 which leads to the outlet 19.

60 The electric current is supplied from suitable service lines 25, 26, and 27, through a switch 28 to conductors 29, 30, and 31, to one end of the coils 32, 33, and 34, of an auto-transformer, the other ends of said coils preferably being connected together as by a bar 35 to provide the proper circuits for a three-phase current.

65 The secondary current passes from the transformer selectively through similar branches of a

series of conductors 36, 37 and 38 and the arms 39, 40, and 41 of a motor-operated switch 42 to the heating elements or ribbons 21, 22, and 23 respectively. The motor-operated switch 42 desirably is controlled by a thermostat 43, which is located in the path of the fluid flowing from the outlet and actuates a switch 44 to vary or reverse the current supplied to the field of the motor 42.

70 Certain liquids, such as linseed oil, and other vegetable compounds, when heated to a predetermined temperature, are subject to chemical or other reaction which causes a further rise in the temperature of the liquid. This is not instantaneous and may take place over an appreciable length of time and under such circumstances it is desirable that an additional thermostat 43x be located in the reactor at a suitable distance from the inlet end thereof and similarly arranged to control the current supplied to the 75 magnetic switch.

76 In the construction shown conductors 45 and 45x lead respectively from the terminal of the switch 44 so that the action of the thermostat upon the switch 44 causes a current to pass 80 through the field 46 of the motor-operated switch in a direction to decrease or increase the voltage and consequently the current supplied to the heating elements, thereby causing the liquid to be heated to a substantially constant 85 temperature.

90 The supply of current to the transformer desirably is controlled by the flow of the fluid in the supply pipe 12. As illustrated herein a conductor 47 connected with the supply conductor 26 leads 95 to the solenoid 48 of the switch 28 and thence to a flow control switch 49 in the liquid supply pipe 12. A return conductor 50 leads from this switch to the supply conductor 27. The switch 49 is so constructed as to actuate the solenoid to 100 maintain the switch 28 in closed position so long as the flow of fluid through the supply pipe 12 continues, but upon interruption of such flow the switch 49 will break the main supply circuit, thereby cutting off the electric current until the 105 flow of liquid in the supply pipe 12 is re-established. By reason of this construction all danger of overheating or injury to the heating elements, or material being heated, is avoided.

110 The liquid passes from the outlet 20 of the heater 3 into the first of the channels 4 of the reactor which are of much greater cross sectional area than the cross sectional area of the conduit through which the liquid flows through the heater. Consequently, the rate of flow of the 115 liquid through the reactor is very materially reduced.

120 The reactor may be of any suitable form, but as illustrated herein in Figs. 2, 3, and 4, comprises a substantially rectangular tank or container 125 constructed of or provided with a lining 51 of aluminum, or other material having non-corrosive properties. A series of vertical partitions 52 extend from near the bottom of the reservoir nearly to the top thereof, leaving a vapor space 130 above the upper ends of the partitions. Alternating partitions 53 extend from the bottom of the reservoir in parallelism with the partitions 52, but terminate sufficiently short of the partitions to permit the column of liquid, of substantially 135 uniform cross-sectional area, to flow from one channel to the other without overflowing the top of the partitions 52.

140 The spaces between the partitions 52 and 53 are provided with outlet pipes 54 which communi- 145

cate with a common conduit 55 and are provided with valves 56 by which any one of the series of pipes 54 may be opened to permit the liquid to flow from the selected outlet conduit 54 to the conduit 55, and also to withdraw the liquid from the spaces between the partitions 52, 53, when it is desired to empty the reactor.

The tank or container is supported upon a series of girders 57 and is surrounded by suitable insulation 58 which in turn is surrounded by a casing 59. The top of the container is closed by a cover 60 having handles 61 to permit its removal. An outlet pipe 62 for the liquid leads from the upper end of the container remote from that into which the liquid is supplied through the heater 2. A pipe 63 leads from the space above the upper ends of the partitions to an exhaust fan 64 which maintains a partial vacuum in the space above the flowing liquid in the reactor and serves to withdraw any acid or other fumes which may be in the liquid or formed during the polymerization process. A pipe 65 leads from the fan 64 to a suitable condenser 66.

Under certain conditions it is found advisable to maintain the space above the liquid in the reactor filled with carbon-dioxide or other neutral gas. This may be accomplished by introducing such a gas through an inlet pipe 65x at or near the inlet end of the reactor.

Inasmuch as air is excluded from the space above the liquid, oxidation of the liquid is prevented and deterioration of the product, which occurs when polymerization of oil is accomplished in open kettles, is entirely avoided, so that a pure bodied liquid is obtained.

Suitable means are provided for maintaining the liquid in the reactor at the desired substantially constant polymerizing temperature throughout the entire passage of the liquid through the reactor. This is accomplished in the present invention by providing heating units, such as plates 67 of high resistance which preferably lie in close proximity to, but electrically insulated from, the side walls 51 of the receptacle. Suitable terminals for the conductors 68 of the heating current extend through the insulation and outer walls of the reactor.

Any suitable means may be provided for supplying an electric heating current to the plates 67, such as a separate auto-transformer, of the character herein described, supplied from the main circuit, or independent means subject to thermostatic regulation operable to maintain a predetermined constant temperature of the fluid in the reactor may be employed.

The reactor is of such length and the partitions 52 and 53 are so spaced apart as to provide a continuous channel of sufficiently greater cross-sectional area than that of the conduit in the heater 60 to retard the flow of liquid through the reactor such predetermined time as is necessary to effect the desired degree of polymerization.

If a lesser degree of polymerization of oil is required, or if liquids requiring a shorter period of uniform predetermined temperature are being treated, the channel through which the liquid passes may be shortened by opening one of the valves 56 to discharge the liquid from the lower end of a selected channel directly into the conduit 55 from which it may be carried to a suitable cooling device adapted to arrest polymerization or other action.

Inasmuch as the polymerization of oil, or other liquid, is dependent upon the degree of constant temperature to which the liquid is subjected, and

the time interval during which it is subjected to such temperature, a proper degree of polymerization may also be established by causing the confined stream of liquid to flow at a predetermined constant rate and regulating the temperature in correlation thereto.

One of the features of the present invention consists in quickly cooling the liquid after the required degree of polymerization has been effected. This is accomplished in the present invention by heat exchange between the liquid in the final or outlet compartment of the reactor and the inflowing fresh liquid which is supplied to the heater. In the construction illustrated in the drawings the pipe 16, through which the liquid is pumped to the heater, is provided with an upwardly extending sinuous section 14 located in the final compartment 5 of the reactor.

By virtue of this heat exchange the liquid supplied to the heater is pre-heated from the heat extracted from the liquid being delivered from the reactor which otherwise would be wasted, thereby effecting the saving of considerable expense in the operation of the apparatus.

Among the numerous advantages attained by the present invention the following are of primary importance:—

(a) The liquid being treated is passed through a heating conduit of small cross sectional area having electrically heated walls of non-corrosive metal at such a rate that the heating requires a very short interval of time, and inasmuch as the liquids are processed in a system closed from the atmosphere the liquid can be safely heated to much higher temperatures than can be attained in open kettle methods. This results in a very great saving of time over that required by previous processes and consequently results in a greater output of polymerized or bodied liquid.

(b) The liquid, after thus being highly heated, passes directly into a reactor which, by reason of its lining of non-corrosive material, will have no effect upon the liquid. As the liquid passes through the reactor its rate of flow is so retarded that it may be maintained the required length of time at the proper constant polymerizing temperature, and when passing from the last compartment of the reactor the liquid is quickly cooled sufficiently to arrest the polymerizing action and to enable the liquid to be discharged from the reactor immediately to a storage tank. The process, therefore, permits the continuous production of bodied oil as distinguished from intermittent production heretofore employed.

(c) The fume or vapor loss is reduced to a minimum. This results in a very important saving of the liquid as in usual processes where oil is maintained in open kettles at high temperatures, for a considerable period of time, the fume or vapor loss may amount to eight per cent or more by weight of the liquid being processed.

(d) There is no substantial decomposition of the oil which would produce solid products, and moisture, acid, and other volatile products are effectively withdrawn.

(e) The processing is wholly automatic and labor cost is reduced to a minimum.

(f) As the temperature to which the liquid is subjected, and the time during which it is so subjected are always under close automatic control, a very clear, heavy bodied liquid of high and uniform quality is obtained at a cost of approximately one-third of that involved in the old direct fired method of bodying.

While the invention has been described partic-

ularly with reference to the polymerizing or bodying of oils, and similar material, it is obvious that its use may be extended to other fields in which it is desirable to subject materials to a predetermined uniform temperature for a predetermined period of time for the purpose of modifying the chemical or physical characteristic of such materials.

It is further to be understood that while in the present embodiment of the invention electric heating apparatus has been particularly described, other types of heating apparatus capable of performing similar functions may be employed.

It is also to be understood that the particular form of apparatus disclosed herein for performing the process is of an illustrative character and that various changes in form, construction and arrangement of parts may be made within the spirit and scope of the following claims.

Having thus described the invention, what is claimed as new, and desired to be secured by Letters Patent, is:

1. The method of continuously bodying unsaturated oils of the ester type capable of polymerization which comprises confining a continuously flowing stream of the liquid oil of small cross sectional area from contact with the air, electrically heating the flowing stream of small cross sectional area rapidly to a predetermined polymerizing temperature, thereupon enlarging the cross sectional area of the flowing stream, subjecting the enlarged stream of flowing liquid to heat exchange to hold it at substantially the same constant polymerizing temperature, varying the rate of flow of the liquid to maintain it at said polymerizing temperature for a predetermined period of time correlated to said constant temperature sufficient to effect the desired degree of polymerization and then quickly cooling the liquid to arrest polymerization.

2. The method of continuously bodying unsaturated oils of the ester type capable of polymerization which comprises confining a continuously flowing stream of the liquid of small cross sectional area from contact with the air, electrically heating the flowing stream of small cross sectional area rapidly to a predetermined polymerizing temperature, thereupon enlarging the cross sectional area of said flowing stream, electrically heating the enlarged stream of flowing liquid to the same polymerizing temperature, varying the rate of flow of the liquid to maintain it at said polymerizing temperature a predetermined period of time correlated to said constant temperature sufficient to effect the desired degree of polymerization, and then quickly cooling the liquid to arrest polymerization.

3. The method of continuously bodying unsaturated oils of the ester type capable of polymerization which comprises confining a continuously flowing stream of the liquid of small cross sectional area from contact with the air, electrically heating the flowing stream of small cross sectional area rapidly to a predetermined polymerizing temperature, thereupon enlarging the cross sectional area of said flowing stream, electrically heating the enlarged stream of flowing liquid to the same polymerizing temperature, varying the rate of flow of the liquid to maintain it at said polymerizing temperature a predetermined period of time correlated to said constant temperature sufficient to effect the desired degree of polymerization, removing from the enlarged stream the volatile products liberated by the liquid while subjected to said polymerizing

temperature, and then quickly cooling the liquid to arrest polymerization.

4. The method of continuously heat-treating unsaturated oils of ester type capable of polymerization which comprises confining a continuously flowing stream of the liquid of small cross sectional area, confined from contact with the air, electrically heating the flowing liquid rapidly to a predetermined temperature thereupon enlarging the cross sectional area of said stream, electrically, maintaining the enlarged stream of flowing liquid constantly at substantially said temperature throughout such distance as to correlate the period of time to which said enlarged stream is subjected to said substantially constant temperature as to effect the desired degree of physical or chemical change in said liquid, then quickly cooling the liquid to arrest such change by heat exchange with the fresh liquid which maintains the flowing stream.

5. The method of continuously bodying unsaturated oils of ester type capable of polymerization which comprises electrically heating quickly a rapidly flowing stream of said liquid of small cross sectional area, confined from contact with the air, to a desired polymerizing temperature, thereupon enlarging the cross sectional area of the stream of liquid to reduce the rate of flow of said liquid and electrically maintaining the enlarged stream of liquid at substantially the same constant polymerizing temperature, regulating the distance of flow of said enlarged stream in correlation to the substantially constant temperature to provide the period of time required to effect the desired polymerization of the liquid, and then quickly cooling the flowing stream to arrest polymerization.

6. The method of continuously bodying unsaturated oils of ester type capable of polymerization which comprises quickly electrically heating a flowing stream of said liquid of small cross sectional area, confined from contact with the air, to a desired polymerizing temperature, thereupon enlarging the cross sectional area of the stream of liquid for a predetermined distance and electrically maintaining the enlarged stream of liquid at substantially the same constant polymerizing temperature, controlling the heat supplied to the enlarged stream of flowing liquid in correlation to the rate of flow of said stream to maintain the liquid at said polymerizing temperature for the predetermined period of time required to effect the desired polymerization, and then quickly cooling the flowing stream to arrest polymerization.

7. An apparatus for continuously bodying liquids capable of polymerization comprising a chamber having therein continuous concentrically arranged, narrowly spaced, parallel walls of material of high electrical resistance providing a long conduit of small cross sectional area for the liquid, means for supplying an electric heating current to said walls to heat the flowing stream of liquid quickly, a reactor communicating with said conduit having a channel therethrough of such larger cross sectional area than said conduit as to retard the flow of liquid therethrough for a predetermined length of time, means for maintaining the liquid in said reactor at substantially the same polymerizing temperature during said predetermined length of time thereby to produce the desired degree of polymerization, and means for quickly cooling the flowing stream discharging from said reactor to arrest polymerization.

8. An apparatus for continuously bodying liq-

- uids capable of polymerization comprising a chamber having therein continuous concentrically arranged, narrowly spaced, parallel walls of material of high electrical resistance providing 5 a long conduit of small cross sectional area for the liquid, means for supplying an electric heating current to said walls to heat the flowing stream of liquid quickly, a reactor communicating with said conduit, means for maintaining 10 the liquid in said reactor at substantially the same polymerizing temperature a predetermined length of time sufficient to produce the desired degree of polymerization, means for quickly cooling the flowing stream discharging from said reactor to arrest polymerization, and means including a thermostat subject to the temperature of the liquid discharged from said conduit into 15 said reactor for varying said heating current to maintain the liquid discharging into the reactor 20 at a substantially constant predetermined polymerizing temperature.
9. An apparatus for continuously bodying liquids capable of polymerization comprising a conduit for the liquid of small cross sectional area 25 having walls of high electrical resistance material, means for supplying an electric heating current to said wall to heat the liquid quickly to a predetermined polymerizing temperature, a reactor communicating with said conduit comprising 30 a closed chamber having alternately disposed baffles arranged to provide a channel of substantially uniform but greater cross sectional area than that of said conduit and of such length as to require a predetermined period of time for 35 the liquid flowing from said conduit to pass therethrough correlated to the predetermined polymerizing temperature to effect the desired polymerization of the liquid, means for electrically heating the liquid in said reactor to maintain it constantly at substantially said polymerizing temperature during its passage through said channel, an outlet passage from said reactor, and means for quickly cooling the liquid discharging from said reactor by heat exchange of the liquid supplied to said heating conduit.
10. An apparatus for continuously bodying liquids capable of polymerization comprising a conduit for the liquid of small cross sectional area having walls of high electrical resistance 50 material, means for supplying an electric heating current to said wall to heat the liquid quickly to a predetermined polymerizing temperature, a reactor communicating with said conduit comprising a closed chamber having alternately disposed baffles arranged to provide a channel of substantially uniform but greater cross sectional area than that of said conduit and of such length as to require a predetermined period of time for 55 the liquid flowing from said conduit to pass therethrough correlated to the predetermined polymerizing temperature to effect the desired polymerization of the liquid, means for electrically heating the liquid in said reactor to maintain it constantly at substantially said polymerizing temperature during its passage through said channel, an outlet passage from said reactor, and means for quickly cooling the liquid in said outlet passage, and means for exhausting the vapors liberated from said liquid while subjected 60 to said polymerizing temperature.
11. An apparatus for continuously bodying liquids capable of polymerization comprising a conduit for the liquid of small cross sectional area having walls of high electrical resistance material, means for supplying an electric heating 65 current to said wall to heat the liquid quickly to a predetermined polymerizing temperature, a reactor communicating with said conduit comprising a closed chamber having alternately disposed baffles arranged to provide a channel of substantially uniform but greater cross sectional area than that of said conduit and of such length as to require a predetermined period of time for the liquid flowing from said conduit to pass therethrough correlated to the predetermined polymerizing temperature to effect the desired polymerization 70 of the liquid, and means for electrically heating the liquid in said reactor to maintain it at substantially said polymerizing temperature during its passage through the channel.
12. An apparatus for continuously bodying liquids capable of polymerization comprising a conduit for the liquid of small cross sectional area having walls of high electrical resistance material, means for supplying an electric heating current to said wall to heat the liquid quickly to a predetermined polymerizing temperature, a reactor communicating with said conduit comprising a closed chamber having alternately disposed baffles arranged to provide a channel of substantially uniform but greater cross sectional area than that of said conduit and of such length as to require a predetermined period of time for the liquid flowing from said conduit to pass therethrough correlated to the predetermined polymerizing temperature to effect the desired polymerization of the liquid, means for electrically heating the liquid in said reactor to maintain it constantly at substantially said polymerizing temperature during its passage through said channel, and a plurality of outlet pipes communicating with said reactor at different 40 distances from the intake end thereof having respectively valves operable to vary the effective length of the reactor channel and thereby to vary the period of time required for the liquid to pass therethrough.
13. An apparatus for continuously bodying liquids capable of polymerization comprising a chamber having narrowly spaced, parallel walls, a plurality of thin ribbons of high electrical resistance material arranged concentrically in substantial parallelism and at their edges set in grooves in said walls to provide a plurality of conduits for the liquid of small cross sectional area, means for supplying an electric heating current to said ribbons in such a manner as to cause current to pass through alternating ribbons in opposite directions to counteract the effect of self induction, a reactor communicating with said conduit having a channel for the liquid of greater cross sectional area than that of said heating conduit and of such length as to require a predetermined period of time for the liquid flowing from the conduit to pass therethrough correlated to the predetermined polymerizing temperature to effect the desired polymerization of the liquid, and means for electrically heating the liquid in said reactor to maintain it at substantially said polymerizing temperature during its passage through the channel.
14. An apparatus for continuously bodying

liquids capable of polymerization comprising a conduit for the liquid of small cross sectional area having walls of high electrical resistance material, means for supplying an electric heating current to said wall to heat the liquid quickly to a predetermined polymerizing temperature, a reactor communicating with said conduit comprising a closed chamber having alternately disposed baffles arranged to provide a channel of substantially uniform but greater cross sectional area than that of said conduit and of such length as to require a predetermined period of time for the liquid flowing from said conduit to pass therethrough correlated to the predetermined

polymerizing temperature to effect the desired polymerization of the liquid, means for electrically heating the liquid in said reactor to maintain it constantly at substantially said polymerizing temperature during its passage through said channel, an outlet passage from said reactor, means for quickly cooling the liquid in said outlet passage, means for continuously supplying liquid to said conduit, and means operable upon cessation of flow of said liquid to break electric heating current during the cessation of flow. 5 10
